Primary Examiner — Cynthia Ramirez*Assistant Examiner* — Llorellys Martinez-Rivera(74) *Attorney, Agent, or Firm* — Michael J. Feigin, Esq.; Feigin & Associates, LLC(57) **CLAIM**

The ornamental design for a gem setting in basket, as shown and described.

DESCRIPTION

FIG. 1 is a top perspective view of a gem setting in basket showing our new design;

FIG. 2 shows a bottom perspective view thereof.

FIG. 3 shows a top plan view thereof.

FIG. 4 shows a bottom plan view thereof; and,

FIG. 5 shows a left side elevation view, the opposite side being a mirror image thereof.

The broken lines in the drawings illustrate portions of the gem setting in basket that form no part of the claimed design.
